Patented Aug. 24, 1971

221,566

TOY TRUCK CAB

Ira Gilford, Thousand Oaks, Calif., assignor to Tonka Corporation, Mound, Minn.

Filed July 27, 1970, Ser. No. 24,128

Term of patent 3½ years

Int. Cl. D21—01

U.S. Cl. D34—15

FIG. 1 is a front, left side and top perspective view of the toy truck cab showing my new design; and

FIG. 2 is a top plan view thereof; and

FIG. 3 is a front elevational view thereof; and

FIG. 4 is a left side elevational view, the right side being a mirror image thereof; and

FIG. 5 is a rear elevational view thereof.

I claim:

The ornamental design for a toy truck cab, as shown and described.
